[57] **CLAIM**

The ornamental design for a cover for a vacuum cleaner, as shown and described.

DESCRIPTION

FIG. 1 is a top perspective view of a cover for a vacuum cleaner showing my new design;

FIG. 2 is a top plan view thereof;

FIG. 3 is a rear elevational view thereof;

FIG. 4 is a front elevational view thereof;

FIG. 5 is a right side elevational view thereof, the left side elevational view being a mirror image of the right side view; and,

FIG. 6 is a bottom plan view thereof.

FIG 1

FIG. 6

FIG. 5

FIG. 3

FIG. 2
